CLAIM

The ornamental design for a flashlight, as shown and described.

DESCRIPTION

FIG. 1 is a front view of the flashlight showing my new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a front perspective view thereof;

FIG. 8 is a rear perspective view thereof;

FIG. 9 is a front perspective view thereof, illustrating the flashlight at an operated condition when a handle is pulled to extend its length; and,

FIG. 10 is a front perspective view thereof, illustrating the flashlight at the operated condition.

Throughout the drawings the broken lines depict portions of the flashlight that form no part of the claimed design.
